DESIGN FOR A WEIGHING SCALE

Jean O. Reinecke, Chicago, Ill., assignor to Continental Scale Corporation, Chicago, Ill., a corporation of Delaware

Application April 8, 1939, Serial No. 84,155

Term of patent 7 years

To all whom it may concern:

Be it known that I, Jean O. Reinecke, a citizen of the United States, residing at Chicago, Cook County, Illinois, have invented a new, original, and ornamental Design for a Weighing Scale, of which the following is a specification, reference being had to the accompanying drawing, forming a part thereof.

Referring to the drawing:

Fig. 1 is a perspective view of a weighing scale embodying my new design;

Fig. 2 is a side elevational view thereof on a larger scale; and

Fig. 3 is a front elevation of the scale shown in Fig. 2.

I claim:

The ornamental design for a weighing scale, as shown.

JEAN O. REINECKE.
